UNITED STATES PATENT OFFICE

GALEN EVANS, OF SHELTON, NEBRASKA

WELL

Application filed May 5, 1930. Serial No. 449,914.

My invention relates to wells, the present invention being in the nature of an improvement or modification of the well casing and method of sinking described in my prior Patent No. 1,733,953, granted October 29, 1929.

5 The primary object of my invention is the provision of the structure and of a method of sinking the structure through quick sand, at the same time utilizing the quick sand as ballast to facilitate the sinking of the well casing.

10 Another object of the invention is the provision of a method of forming an outer layer of gravel around the well casing by removing the fine sand through the interior 15 of the well casing during the sinking.

15 Another of my objects is the provision of a method for separating the water from the sand and gravel entering the well casing, of 20 utilizing the separated water for cutting out the soil underneath the well casing and for utilizing the separated sand and gravel as ballast for sinking the well casing, the separated sand and gravel being subsequently re- 25 moved from the interior of the well casing after the casing has been sunk to the desired depth.

Another object of the invention is the provision of the well casing having a bottom and 30 a false bottom to divide the well casing into a lower closed water chamber and into an upper ballast chamber which is open at its top.

Having in view these objects and others 35 which will be pointed out in the following description, I will now refer to the drawing, in which

Figure 1 is a median vertical sectional view 40 of my well casing when completed, portions being shown in full lines or with broken away parts to more clearly disclose which would otherwise be hidden.

Figure 2 is a view in greatly reduced scale showing the under surface of the well casing.

45 The well casing is designated by the numeral 10. This may be made of any suitable material such as wood, sheet metal or concrete but it is essential that the casing be so made as to provide numerous relatively large 50 openings therethrough. When the casing is

made of sheet metal the openings are punched in suitable size. In a concrete casing an exceedingly lean mixture of cement with very coarse gravel would be employed so as to produce a very porous casing wall. When wood is used for forming the casing wall, 55 planks are arranged and bound together in cylindrical form with the meeting edges of the planks spaced at a sufficient distance to permit the passage of the finer sand and of all other sand up to coarse gravel. The purpose of this construction will be explained subsequently but it is based on the fact that a layer of coarse gravel surrounding the well casing is the most effective filter for preventing the entrance of fine sand to the interior 60 of the well casing.

Regardless of the material of which the well casing is constructed, the method of sinking throughout its first stages is a method 65 which is common in the art. There are in fact several methods by which this well casing could be sunk depending on the character of the soil into which the well casing is to be sunk. The present methods contemplate the sinking of the well casing into or through a 70 layer of fine sand or of quick sand and the novel steps of the method relate particularly to the sinking of the well casing into or through such a layer.

75 When the well casing has been sunk to or in proximity to the water table, the sinking is temporarily halted and the casing is provided with a bottom 11 and with a false bottom 12. The bottom 11 is provided near its periphery with a plurality of apertures arranged concentrically, each aperture communicating with a tangentially disposed channel on the under side of the bottom 11, the channels 13 being open on their under sides as shown in Figure 1. Pipes or tubes 80 14 are inserted through the openings in the bottom 11 with their upper open ends in the top of the chamber between the two bottoms 11 and 12. The chamber thus formed between the two bottoms is the water chamber 85 90 with outlets through the pipes 14.

The two bottoms 11 and 12 are provided with central openings in vertical alignment. These openings are preferably large enough to permit a boy or a small-sized man to pass 100

through them. The tube 15 is passed through both of these openings to project above the water table. As in my prior patent, the tube 15 is in sectional form so that 5 additional sections may be added to the tube during the sinking of the well casing so as to maintain the working parts above the water body of the well. The tube 15 is provided with a large number of apertures 16 throughout its length, the apertures being 10 designed to permit the passage of water therethrough but to retain the sand. The tube 15 serves not only as a filter but it also 15 serves as a casing for the pump which is used in the sinking of the well casing.

The pump 17 is seated within the tube 15 and it is provided with a suction pipe 18. This suction pipe 18 telescopes into the pipe 19 so that the pump 17 with its suction pipe 20 18 may be raised without disturbing the position of the lower or inlet end of the pipe 19. The suction pipe 18 fits snugly but slidably in the pipe 19 so that the pipe 19 becomes in effect an extension of the suction pipe 18. 25 The pump 17 carries the sand, gravel and water from beneath the bottom 11 of the well casing and discharges the sand, gravel and water through the gooseneck discharge pipes 20.

3 In the sinking operation of the well casing the sand, gravel and water are carried upwardly through the pipes 18 and 19 through the pump 17 and the gooseneck discharge pipes 20 to the upper channel of the well casing above the false bottom 12. This mass 35 of material is packed into the upper chamber surrounding the tube 15 but the water is filtered from the sand and gravel and is permitted to flow down through the interior of 40 the tube 15 to the excavated chamber below the bottom 11. The water rushes down through the tube 15 with sufficient force to loosen the soil immediately beneath to provide a soil cutting action at the nose of the 45 well casing. At the same time the lower chamber of the well casing contains the water which filters through the openings in the well casing, through the wall bottom 12 and also the back flow from the tube 15. In this 50 manner the lower chamber is normally kept almost full of water at all times during the sinking operation. At the same time considerable fine sand enters through the wall of the well casing to form an irregular layer 55 as outlined in Figure 1. The water of the lower chamber pours through the pipes 14 and is directed tangentially when it reaches the excavated chamber beneath the well casing. This water also has considerable force 60 so that its tangential movement beneath the bottom of the well casing causes the water to swirl and to thus loosen and cut away the soil in proximity to the lower edge of the well casing. This process is continuous 65 throughout the sinking of the well casing and

more especially throughout that stage of the sinking in which the well casing passes through a stratum of fine sand or of quick sand.

After the well casing has been sunk to a 70 depth where its upper edge is in proximity to the water table, forms are set up and the concrete walls are cast in the form shown at 75 21 and 22 in Figure 1. The wall 22 is cylindrical and axial with respect to the casing 10. The reduced diameter of the wall 22 as compared with the wall 10 affords greater strength for that portion of the casing which is subjected to frost and erosion. At this point in the sinking of the casing it is necessary that the discharge of the sand, gravel and water from the pump be outside the well casing since the upper chamber has become gradually filled with sand and gravel. The pump 17 may also be raised but the goose-neck outlets 20 must be raised so that their discharge will be over the upper edge of the wall 22. The outlet discharge pipes 20 are so connected with the pump 17 that they may be turned around their vertical axes so as to permit their passage through the portion 22 of the casing. They can then be turned into radial position so as to discharge over the edge of the wall 22. It is desirable in this connection that one or more reservoirs 95 23 be provided for taking care of the discharged material. These reservoirs 23 may be made to function as settling basins so that the water from the top may be flowed back into the well and through the tube 15 to assist in the further excavation of the chamber beneath the bottom of the well.

After the casing has been sunk to the desired depth the lower chamber will be found to be full of water with an irregular layer 105 of fine sand in the bottom portion. The upper chamber will be full of a compressed mass of moist sand and gravel. It is necessary in completing the well that the sand and gravel from the upper chamber as well as the fine sand in the lower chamber be removed. For this purpose I have provided a plurality of gates 24, 25 and 26. The number of gates in the pipe 15 may be varied at will and I have shown three in my drawing 110 merely for the purpose of explaining their function.

When the well has been sunk to the desired depth in which the casing is to remain, the uppermost gate 24 is opened while the pumping action is going on. It should be explained that the gates all have outside controls similar to the controls illustrated and described in my prior patent. The opening of the gate 24 permits the sand from 120 the upper chamber to enter the tube 15 and this sand is washed into the tube by means of water flowing in from the reservoirs 23. The sand and gravel from the upper chamber is passed through the tube 15 to the 125

chamber underneath the floor 11 where they are immediately caught in the suction pipes 18 and 19 and carried to the reservoirs 23. This step proceeds until the level of the sand 5 and gravel in the upper chamber is on a level with the bottom of the gate 24. At this point the gate 25 must be opened to repeat the processes for removing the sand and gravel from above the level of the gate 25. 10 The final opening of the gate 26 removes the fine sand from the lower chamber. At this point the well casing will be relatively free of all sand and gravel but the open nature of the wall 10 permits the continued entrance of fine sand. The pumping action must be kept up until all the fine sand surrounding the wall 10 is removed. This leaves the wall 10 with a layer of gravel which is recognized as the most effective filter for 15 fine sand.

Prior methods of utilizing such a filter contemplate excavation surrounding the well casing and the filling of the excavation with gravel which has been screened from the fine sand. My method utilizes the wall 10 of the well casing as a screen and it accomplishes the same results as in prior methods but at 20 an enormous reduction in cost. My method furthermore leaves the well casing in a position so that it acts continuously as a screen so that it can never become clogged with fine sand, this being one of the very serious difficulties encountered with the prior methods.

The well is completed as described in my 25 prior patent. The pipes 15 and the suction pipes 18 and 19 together with the pump 17 are removed from the casing. The central opening in the bottom 11 may or may not be plugged up, depending on the character of the soil underneath the bottom 11. If necessary, the opening may be plugged in the manner described in the prior patent.

In using the word "soil" it is to be understood that I refer to clay, sand, gravel and in fact to all solid materials naturally found in the soil stratum into which or through which the well casing is sunk. I refer to the two chambers of the well casing as a water chamber and as a ballast chamber but these 50 terms are used merely for the purpose of distinguishing between the two chambers and not because these terms are exclusive. The ballast chamber contains much water in addition to the sand and gravel, all of which are delivered from the bottom of the well cavity into the ballast chamber. Likewise the water chamber contains sand which filters through the casing walls and this together with the great body of water in the water 55 chamber serves as ballast for increasing the weight of the well casing during the sinking process.

Having thus described my invention in such full, clear, and exact terms that its 60 construction and operation will be readily

understood by others skilled in the art to which it pertains, what I claim as new and desire to secure by Letters Patent of the United States is:

1. A well casing having a porous outer wall 70 for admitting fine sand from a soil stratum of water bearing sand and gravel, a bottom and a false bottom in said well casing and forming a lower closed water chamber and an upper ballast chamber, and means for discharging the ballast from the upper chamber after said casing has been sunk to the desired depth.

2. A well casing having a porous outer wall 80 for admitting fine sand from a soil stratum of water bearing sand and gravel, a bottom and a false bottom in said well casing and forming a lower closed water chamber and an upper ballast chamber, means for continuously discharging the water from the upper portion of the water chamber, said 85 means coating with means for imparting a tangential swirl to the discharged water immediately underneath said bottom, and means for discharging the ballast from the upper chamber after said casing has been sunk to the desired depth.

3. A well casing having a bottom and a false bottom dividing said well casing into a ballast chamber and a water chamber, said water chamber having openings in the walls thereof for freely admitting water and fine sand thereinto, means for conducting water and soil from beneath said well casing into the ballast chamber thereof, means for conducting a continuous stream of water from said water chamber to the cavity beneath said well casing during the sinking of said well casing, and means for discharging the ballast from said ballast chamber and the 90 fine sand from said water chamber after said well casing has been sunk to the desired depth.

In testimony whereof I affix my signature. 95
